UNITED STATES PATENT OFFICE.

EDWARD SCHWARTZ, OF CHICAGO, ILLINOIS, ASSIGNOR TO WM. E. SLAUGHTER CO., OF CHICAGO, ILLINOIS, A CORPORATION OF ILLINOIS.

ELECTRICALLY-HEATED COMB.

1,052,097.

Specification of Letters Patent.

Patented Feb. 4, 1913.

Application filed August 15, 1912. Serial No. 715,204.

To all whom it may concern:

Be it known that I, EDWARD SCHWARTZ, a citizen of the United States of America, and a resident of Chicago, county of Cook, 5 and State of Illinois, have invented certain new and useful Improvements in Electrically-Heated Combs, of which the following is a specification.

The main objects of this invention are to 10 provide a simple, improved and comparatively inexpensive form of electrically heated hair drier and comb.

An illustrative embodiment of this invention is shown in the accompanying drawings in which—

Figure 1 is a perspective view. Fig. 2 is a longitudinal section taken on the line A—A of Fig. 3. Fig. 3 is a transverse section taken on the line B—B of Fig. 2. Fig. 20 4 is a detail of the electrical connection between the heating element and the conductors leading to the source of electricity. Fig. 5 is a detail of the collar which prevents relative rotation of the comb and 25 handle.

In the construction shown in the drawings, the comb comprises inner and outer tubular casings 1 and 2, the inner casing 1 extending beyond the outer casing 2 at its 30 inner end and having the handle 3 mounted thereon and rigidly connected at 4 where the casing 1 is expanded. A sleeve or collar 5 is interposed between the outer casing 2 and the handle 3 and has a pair of shoulders 35 6 spaced to provide a notch between them, and a pair of prongs 7 adapted to extend into the handle for preventing the relative rotation. The outer casing 2 has rigidly mounted thereon the tooth section of the 40 comb 8 and is preferably made of a strip of sheet metal bent to cylindrical form as shown in Fig. 3, and having its longitudinal edge portions brought together so as to stand outward in the form of a single projecting rib or wing 9. These edge portions are perforated at 10. The tooth section 8 is constructed preferably of softer metal than the casing 2, such, for example, as aluminum, and has a pair of projecting back flanges 12 which are spaced apart to provide 50 a groove or recess between them for the reception of the rib 9. When the projecting rib 9 is inserted into the groove, a heavy pressure is exerted against the outer faces 55 of the flanges 12 to force a portion of the

relatively softer material of the flanges into the openings 10 and thereby rigidly bind the sections together.

The heating element comprises a central metal reinforcing rod 13 upon which are 60 slipped two tubes 14 and 15 of lava or other suitable insulating material, and a resistance coil 16 of fine wire which is wound on the tubes. The coil is more closely wound on the tube 14 than on the tube 15 for obvious reasons. Wrappings or sleeves of insulating material 17 space the coil 16 from the casing 1. The terminal portions 18 and 19 of the winding are connected to the conductors of the cord 20 within the hollow handle 3, the connection comprising a rectangular block 21 of insulating material having thereon two binding posts 22 and 23 whereby the connections are made. This block has transverse bores for the posts and 70 a longitudinal bore extending inward from one end to meet the adjacent transverse bore. A bushing 24 of insulating material locked in place by a set screw 25 prevents withdrawal or lengthwise movement of the 80 heater.

The outer ends of the casing 1 and 2 are closed by an ornamental plug 26.

In assembling the heater, one end portion 19 of the resistance wire is first threaded 85 through the tubes 14 and 15; the rod is inserted into the tubes alongside of the resistance wire and the coil is then wound on the exterior of the tubes. Then the wrappings 17 are placed in position and finally the 90 connection to the cord 20 is made. This involves first threading the wire 19 into the longitudinal bore and out through the adjacent transverse bore of the block 21, then inserting the rod 13 into the longitudinal 95 bore beside the wire and finally fastening all of the wires by the binding posts as shown. The post 23 secures the end portion 19 of the coil, the corresponding conductor terminal of the cord and also clamps 100 the rod by compressing the block 21.

To operate the device the socket plug 30 is screwed into a lamp socket in the usual manner. The current being then turned on 105 operates the heater which transmits the heat through the casings to the teeth 8 of the comb, the coil being so proportioned as to prevent overheating.

Although but one specific embodiment of this invention has been herein shown and 110

described, it will be understood that numerous details of the construction shown may be altered or omitted without departing from the spirit of the invention as defined 5 by the following claims.

I claim:—

1. In a device of the class described, the combination of a casing; a heating element therein comprising a tube of insulating material; a reinforcing rod extending lengthwise through said tube; a resistance coil wound upon said tube, said resistance coil having one of its terminal portions threaded through said tube beside said rod; and a 10 terminal block of insulating material having a longitudinal bore for the reception of said rod and terminal portion of the coil, 60 and having a transverse aperture intersecting the first; and a binding post in said transverse aperture adapted to complete an electrical connection to said coil and simultaneously compress said block to secure said 65 rod.
  2. In a device of the class described, the combination of a casing; a tubular handle rigidly mounted on said casing; a heating element adapted to be inserted in said casing comprising a tube of insulating material having a bore throughout its entire length; a resistance coil wound upon said member of insulating material having one of its terminal end portions threaded entirely through said bore from end to end; a block of insulating material mounted in said 15 handle adapted to abut the inner end of said tube and having a longitudinal opening extending partly through said block adapted to register with the bore in said tube and adapted to have said terminal end 20 portion threaded through said opening; a pair of binding posts mounted on said block of insulating material for the terminals of said resistance coil; a reinforcing rod adapted to be inserted in the bore of said 25 tube of insulating material, and into said longitudinal opening in said block of insulating material; and means for connecting said terminals with a source of electricity.
  3. In a device of the class described, the combination of a casing having a comb mounted thereon; a heating element therein comprising a tube of insulating material; a reinforcing rod extending lengthwise through said tube; a resistance coil wound upon said tube, said resistance coil having one of its terminal portions threaded 30 through said tube beside said rod; and a transverse aperture adapted to complete an electrical connection to said coil and simultaneously compress said block to secure said rod.
  4. An electrically heated comb comprising a comb section having a tubular back; a handle rigidly secured to said comb section; a heating element extending through said handle and said tubular section and comprising a tube of insulating material having a resistance coil winding thereon; a reinforcing rod extending through said tube, said resistance coil having one of its terminals extending along said reinforcing rod within said tube; and means for connecting the terminals of said resistance coil with a source of electricity.
  5. In a device of the class described, the combination of inner and outer casing sections; a tooth section; a heating element in said inner casing, and a handle mounted on said inner casing, said outer section comprising a strip of metal bent to form a cylindrical member having a pair of projecting wings, said wings having inwardly abutting faces and having transverse openings therein, said tooth section having upwardly disposed flanges extending lengthwise thereof to provide a groove between them to receive said projecting wings, and a portion of the material of said flanges being pressed into said holes for holding said casing and said tooth section rigidly together.
  6. In a device of the class described, the combination of a casing; a heating element housed within said casing; a comb mounted on said casing and comprising a hollow back of tubular form and having a longitudinal rib thereon, said rib being recessed transversely; and a tooth section having a grooved back embracing said rib and having the material of said grooved back compressed so as to be forced into the transverse recesses for rigidly connecting said comb and said hollow back together.
- Signed at Chicago this 9th day of August 1912.

EDWARD SCHWARTZ.
